UNITED STATES PATENT OFFICE.

JOHN DICKASON, OF VEVAY, INDIANA.

FENCE.

SPECIFICATION forming part of Letters Patent No. 340,988, dated May 4, 1886.

Application filed March 1, 1886. Serial No. 193,632. (No model.)

To all whom it may concern:

Be it known that I, JOHN DICKASON, a citizen of the United States, residing at Vevay, in the county of Switzerland and State of Indiana, have invented certain new and useful improvements in Portable Farm-Fences; and I do hereby declare the following to be a full, clear, and exact description of the invention, such as will enable others skilled in the art to which it appertains to make and use the same.

The invention relates to portable fences, and has for its object the construction of a cheap, strong, durable, and portable fence made up in panels secured together by battens.

The invention will be hereinafter described, and particularly pointed out in the claim.

In the accompanying drawings, which form a part of this specification, Figure 1 is a perspective; Fig. 2, a side elevation of one end of a panel; and Fig. 3 is an end view.

The purpose of my invention is to construct board fences in panels which may be built complete in a work-shop, or other convenient place under cover, and conveyed, in large or small numbers, to any place where it is desired to erect a fence.

This fence is of that class which requires no digging of post-holes, as the panels are held between crossed stakes which simply rest upon the ground; but to prevent its being easily blown over by wind or displaced by animals the panels are anchored to the ground at each end between the stakes.

Reference being had to the drawings and the letters marked thereon, A represents panels the full height of the fence to be constructed, and composed of horizontal bars *a*, the number of which may be varied to suit circumstances, and vertical battens *b c*, secured to both sides of the bars opposite to each other, and near the ends thereof. The battens *b c* may be secured to the bars in any suitable manner. Nailing is, however, considered preferable.

In practice I make the bars about one inch thick and from four to six inches wide, and the battens the same thickness and three or four inches wide. The dimensions given may, however, be varied, as desired.

In erecting a fence built in accordance with

my invention the ground is spaced off according to the length of the panels A, and anchors B, having twisted wire *d* around them, are planted in the ground. Two panels are then set in position with the ends of the bars *a b* overlapping, as shown. The stakes C D are then inserted and crossed between the upper two bars, the upper one resting in the crotch formed by the crossed stakes, and the second rail fitting in the crotch below the crossing. The stakes and the panels are now secured together by a continuous wire, which is looped over each stake C D at *e f*, crossed over the top of the upper bar, *a*, and the free end *g* of the wire which forms the loop *f* on stake C, is drawn down on the outside of the stake D, crossed over the outside of the stake C, passed under the second bar to the opposite side of the fence, where it meets the wire *h*, which constitutes the free end of the loop *e*, and is crossed over the upper bar, *a*, in the opposite direction to the wire *g*, drawn down on the outside of stake C, crossed over to the outside of stake D, passed under the second bar around stake C, back again under the bar, around stake D, and forms a connection with wire *g* by a twist, *i*. The wire *d*, secured to the anchor B, is now drawn up on opposite sides of the lower bar, crossed on top of said bar and secured to the stakes C D at *k l*. The wire *d* need not necessarily be wound around the lower bar of the panel, as it may be carried up to any of the bars in the panel.

Should the fence settle, the wires *d*, connected to the anchors B, may be removed from the stakes and the bar and untwisted until the slack is taken up, when the wire may again be drawn up around the bar and secured to the stakes, as in the first instance.

Instead of taking up the slack in the wire secured to the anchor by untwisting it, the slack may be taken up by blocking up the stakes with wood or stones being placed under them.

The stakes may be made of any suitable dimensions which will work up lumber advantageously without loss.

Having thus described my invention, what I claim is—

A fence composed of detachable panels hav-

ing their bars and bottoms permanently secured together and supported by crossed stakes, to which they are secured by a wire wrapping, in combination with an embedded anchor having wire attached thereto and secured to a bar of the panel, and to both of the stakes on opposite sides of the panel, by the free ends of the wire, substantially as described.

In testimony whereof I affix my signature in presence of two witnesses.

JOHN DICKASON.

Wm. E. DYRE.

Correction in Letters Patent No. 340,988.

It is hereby certified that in Letters Patent No. 340,988, granted May 4, 1886, upon the application of John Dickason, of Vevay, Indiana, for an improvement in "Fences," an error appears in the printed specification requiring correction as follows: In line 1, page 2, the word "bottoms" should read *battens*; and that the Letters Patent should be read with this correction therein that the same may conform to the record of the case in the Patent Office.

Signed, countersigned, and sealed this 11th day of May, A. D. 1886.

[SEAL.]

H. L. MULDROW,
Acting Secretary of the Interior.

Countersigned:

M. V. MONTGOMERY,
Commissioner of Patents.
